(57) **CLAIM**

The ornamental design for a decorative candle votive-pebble, as shown and described.

DESCRIPTION

FIG. 1 is an isometric view of a decorative candle votive-pebble according to the present invention;

FIG. 2 is a first side elevational view thereof;

FIG. 3 is a second side elevational view thereof;

FIG. 4 is a third side elevational view thereof;

FIG. 5 is a fourth side elevational view thereof;

FIG. 6 is a plan view thereof;

FIG. 7 is a bottom plan view thereof; and,

FIG. 8 is an isometric view illustrating in phantom apparatus that may hold the candle votive-pebble.

FIG. 8 is provided for context only and forms no part of the claimed design. Also, structures shown in phantom form no part of the claimed design.

The broken lines are for illustrative purposes only and form no part of the claimed design.
